UNITED STATES PATENT OFFICE

AXEL ARNOLD LAWSON, OF BEVERLY, MASSACHUSETTS, ASSIGNOR TO UNITED SHOE MACHINERY CORPORATION, OF PATERSON, NEW JERSEY, A CORPORATION OF NEW JERSEY

MACHINE FOR OPERATING UPON SHEET MATERIAL

Application filed December 17, 1931. Serial No. 581,679.

This invention relates to machines for operating upon sheet material and is herein illustrated as embodied in a machine for punching soles.

5 In manufacturing shoes, the soles of which are attached to the upper by means of cement, soles may be advantageously located relatively to their shoes for the sole attaching operation by mechanism, not invented by me, comprising gages which locate the forepart of the shoe relatively to the forepart of the sole and a gage operable to engage a hole in the heel end of the sole and to move the sole relatively to the shoe until 10 a median line of the sole is positioned along a median line of the bottom of the shoe. In order that the sole and shoe be accurately located relatively to each other the hole in the outsole is advantageously positioned accurately along the median line of the heel end portion of the sole. Accordingly, it is an 15 object of the present invention to provide an improved sole punching machine having mechanism for locating a sole to be punched in such a way that there will be produced in the sole a hole which will be accurately located along the median line of the heel end of the sole.

To this end, and as illustrated, the invention 20 contemplates the provision in a machine for operating upon soles of a tool, illustrated as a reciprocating punch, and novel mechanism for positioning a sole with the median line of its heel end intersecting the axis of the tool. In the illustrated machine, there 25 is provided a work-support mounted for rotation about an axis coincident with that of the tool, and gages carried by the work-support and movable in conjunction with the work support to position a sole with its median line intersecting said axis, whereby the sole is accurately located for the performance 30 of an operation along said median line. Preferably and as illustrated, the gages comprise inner and outer pairs of gages, the outer gages normally being held in inoperative 35 position so that a sole can be readily inserted between the inner gages, and there being in the illustrated machine manually controlled 40 mechanism for releasing the outer gages and

for rotating the work-support to locate the sole relatively to the axis of the tool and subsequently to initiate an operation of the tool.

Other objects and features of the invention 55 will be apparent from the following detailed description when taken in connection with the accompanying drawings and will be pointed out in the claims.

In the drawings,

Fig. 1 is a side elevation of a machine illustrating one embodiment of the invention;

Fig. 2 is a front elevation of a portion of the machine showing the work-support and gages; and

Fig. 3 is a plan view of a portion of the machine showing the work-support and gage mechanisms.

As illustrated in Fig. 1, the machine comprises a frame 10 having an extension 12 in which is mounted a reciprocating punch 14, and a spaced extension 16 which carries a work-support or table 18 having therein a female die 20 arranged for cooperation with the punch 14 to produce holes in work such as a sole 22.

The punch 14 is carried by a slide 24 which is reciprocated in the frame extension 12 by a crank 26 on a rotary shaft 28 arranged to be driven by a fly-wheel 30 upon operation of clutch mechanism including lever 32 under control of the operator.

The table 18 is conveniently mounted for rotation about the axis of the punch 14. To this end the table comprises a head 34 which rests upon ball bearings 36 supported upon a sleeve 38 through which extends a spindle 40 forming an integral part of the head. The table 18 has a portion 42 which extends forwardly beyond the end of the extension 16, and from which depends a bracket 44, the lower end of which surrounds the lower end of the spindle 40 and is secured thereto by a set-screw 46. The entire table assembly is secured in fixed position heightwise of the frame by means of screws 48 which pass through enlarged openings 50 in flange 52 of the sleeve 38. Clearance space 54 is provided between the sleeve and the frame whereby the sleeve, and consequently the table can be adjusted laterally of the axis of the punch 14.

thereby to locate the die 20 in line with the punch. It is to be noted that the die 20 is located in the head 34 in axial alinement with the spindle 40 and sleeve 38 and consequently, when the die is located in operative relation to the punch, the axis of rotation of the table will coincide with the axis of the punch. The construction described thus provides for rotation of the table, to a limited extent, about the axis of the punch without disturbing the operative relationship between the die and punch. The table has an opening 56 extending axially therethrough to provide for the removal of punchings forced through the die 20.

The gages for locating work relatively to the punch 14 comprise inner gages 58 (Figs. 1 and 3) and outer gages 60. The inner gages 58 comprise arms 62 which are pivoted on studs 64 carried by the table 18, said arms being interengaged by means of circular racks 66 with the result that the gages 58 are movable simultaneously through equal distances laterally of the median line of the table which passes through the axis of the punch. The gages 58 are normally urged toward each other by a spring 68 secured to the table and extending into engagement with one of the arms. The inner ends of the gages 58 carry rolls 70 which facilitate the insertion of work, such as the sole 22, between the gages. The gages 58 operate initially to engage the sole upon opposite sides at points near the end thereof and roughly to locate the sole with the median line of the heel-end thereof extending in the general direction of the median line of the table.

The outer gages 60 are pivotally carried by studs 72 upon the bracket 44 (Figs. 2 and 3), the lower ends of the gages being interconnected by teeth 74 and 76 so that these gages also are movable simultaneously through equal distances toward or away from the median line of the table 18. The gages 60 are normally urged toward each other by a spring 78 connecting them. The upper ends of the gages 60 are curved, as indicated by reference characters 80, to provide for line contact with the work regardless of the angularity of the work relatively to the gages. The gages 60 are positioned to engage a sole upon opposite sides at points near the shank thereof.

In order to facilitate presentation of the work, such as the sole 22, to the punch 14, the outermost gages 60 are arranged to be held normally in inoperative position, that is, spread apart. To this end the lowermost of the teeth 74 is arranged to be engaged by a pin 82 which extends through the bracket 44 and is normally forced upwardly against the tooth 74 by a lever 84 pivotally mounted upon the frame. The pin 82 and consequently the gages 60 are arranged to be released by manu-

ally controlled mechanism to be hereinafter described.

For locating work longitudinally of the table 18 there is provided an end gage comprising an abutment 86 forming one end of a slide 88 mounted in a bracket 90 secured to the frame. In order to determine the location of the abutment for soles of different shapes or sizes, the slide 88 is provided with a pin 92 and a knob 94, surrounding the pin, and by which the gage can be moved inwardly or outwardly of the axis of the die 20. The gage is arranged to be locked in adjusted position by means of a plate 96, carried by the bracket 90, and having holes 98 for the reception of the knob 94 which is held in a selected hole by pressure of a spring 100.

The plate 96 has a forwardly extending portion 102 which constitutes a stripper plate and which is provided with an opening 104 through which the punch 14 operates.

Manually controlled mechanism is provided for releasing the gages 60 prior to initiation of an operation of the clutch thereby to ensure location of the work by the gages prior to operation of the punch. To this end, the machine comprises a treadle 106 pivotally mounted upon the frame, and a link connection 108 pivotally secured at its upper end to a lever 110 mounted for rotation upon a stud 112. The lever 110 carries a cam 114 adapted to engage an adjustable pin 116 mounted upon the lever 84. The lever 84 is normally held in raised position by a spring pressed plunger 118, thereby holding the gages 60 in inoperative position, but upon downward movement of the treadle 106, against pressure of a spring 120, the cam 114 moves the lever 84 downwardly to release the gages. To provide for operation of the clutch, the control lever 32 is connected to a link 122 having a rack 124 in mesh with teeth 126 on a lever 128 loosely mounted on the stud 112. The lever 128 is provided with a cam surface 130 which is normally engaged by an abutment 132 on the link 108 to hold the lever in inoperative position. Upon sufficient depression of the treadle 106 an abutment 134 at the upper end of the link 108 will engage the upper surface of the lever 128 and force the lever downwardly to initiate an operation of the clutch thereby to cause a reciprocation of the punch 14. The distance between the abutments 132 and 134 is such that upon depression of the treadle there will be sufficient delay between the release of gages 60 and the operation of the punch to ensure time for operation of the gages in locating the work upon the table.

In the use of the machine, the operator places work such as a sole 22 upon the table 18 and forces the heel end of the sole between the gage rolls 70 until the rear end of the sole contacts with the abutment 86 thus roughly locating the sole with the median

line of the heel end extending along the central portion of the table. The treadle 106 is then operated effecting the release of the outer gages 60 which move inwardly toward the median line of the table to engage opposite sides of the heel end of the sole. During this operation the sole is held against the abutment 86 and as the gages 60 move inwardly, unless the sole is accurately located with the center line thereof in substantial coincidence with the center line of the table, one of such gages will engage the sole prior to the other gage, in which case the spring 78 will move the table 18 angularly until the other gage 60 engages the opposite edge of the sole. During this angular movement gages 58 and 60 will shift the heel end of the sole laterally until the sole is located with its median line intersecting the axis of the die 20, thereby placing it in operative position relatively to the die and to the punch 14. Upon further depression of the treadle 106 the lever 128 will be operated to cause engagement of the clutch thereby to initiate operation of the punch 14 to produce a hole in the sole. In operating upon soles of different lengths the abutment 86 can be so adjusted by means of the knob 94 that the punched hole will be located along the median line of the heel line of the sole at a predetermined distance from the rearmost end thereof.

Having described my invention, what I claim as new and desire to secure by Letters Patent of the United States is:

1. A machine for operating upon soles comprising a reciprocating tool, a work-support mounted for angular movement about the axis of the tool, a pair of gages for engaging a sole positioned upon the work-support at points upon opposite sides of the sole near one end thereof, a second pair of gages for engaging opposite sides of the sole, and means associated with the last-mentioned pair of gages for moving the work-support angularly to locate the sole with a median line thereof intersecting the axis of the tool.

2. A machine for operating upon soles comprising a reciprocating tool, a work-support rotatable about the axis of the tool, a pair of gages mounted upon the work-support for equal and opposite movement relatively to a median line of the support, and means for rotating the work-support to cause both gages to engage opposite sides of a sole positioned upon the work-support to locate the sole with a median line thereof coinciding with the median line of the work-support.

3. A machine for operating upon soles comprising a punch, a work-support mounted for angular movement about the axis of the punch, a pair of gages mounted upon the work-support for equal and opposite movement relatively to a median line of the support passing through the axis of the punch

for engaging opposite side portions of a sole near one end thereof, a second pair of gages mounted upon the work-support outwardly of the first-mentioned gages, and means associated with the second-mentioned gages for moving the work-support about its axis in locating the sole with a median line thereof coinciding with the median line of the work-support.

4. A machine for operating upon soles comprising a reciprocating tool, a work-support rotatable about the axis of the tool, a pair of interconnecting gages carried by the support and adapted to engage opposite sides of a sole at points equidistant from a median line of the support passing through said axis, and means for moving the support angularly to ensure engagement of both gages with the sole.

5. A machine for operating upon soles comprising a punch, a table mounted for rotation about the axis of the punch, gages mounted upon the table for equal and opposite movement relatively to a median line of the table passing through the axis of the punch, and means for moving the gages and table angularly to locate a sole on the table with a median line thereof coinciding with the median line of the table.

6. A machine for operating upon soles comprising a punch, a table movable angularly about the axis of the punch, two pairs of gages mounted upon the table for equal and opposite movement relatively to a median line of the table passing through said axis for engaging opposite sides of a sole positioned upon the table, means for forcing the gages of one pair of gages toward each other to engage the sole, and means for moving the other pair of gages and the table to centralize the sole with a median line thereof coinciding with the median line of the table.

7. A machine for operating upon soles comprising a punching tool, a work-support mounted for angular movement about the axis of the tool, inner gages mounted upon the work-support and movable to engage a sole positioned upon the support at points on opposite sides of the sole near one end thereof, outer gages mounted upon the work-support and movable to engage opposite sides of the sole at points near the shank portion thereof, means for moving the gages and the work-support angularly to locate the sole with a median line thereof intersecting the axis of the tool, and a gage for locating the sole longitudinally relatively to the axis of the tool.

8. A machine for operating upon soles comprising a reciprocating tool, a work-support mounted for angular movement about the axis of the tool, two pairs of gages mounted upon the work-support, the gages of each pair of gages being arranged for equal and opposite movement relatively to a median line of

the work-support passing through the axis of the tool, means for urging the gages of one pair of gages toward each other, means for urging the gages of the second pair of gages toward each other and for causing angular movement of the work-support in locating the sole with a median line thereof coinciding with the median line of the work-support.

9. A machine for operating upon soles comprising, a reciprocating tool, a work-support, inner and outer pairs of gages mounted upon the work-support, the gages of each pair of gages being movable to engage opposite sides of a sole upon the work-support, means for urging the gages of each pair of gages toward each other, means operable normally to hold apart the outer gages, and means operable prior to an operation of the tool for releasing the outer gages.

10. A machine for operating upon soles comprising a frame, a punch mounted for reciprocation in the frame, a work-support mounted in the frame for rotation about the axis of the punch, a pair of interconnected gages mounted upon the work-support for equal and opposite movement relatively to a median line of the work-support passing through the axis of the punch, means for normally holding the gages apart in inoperative position relatively to a sole positioned upon the work-support, manually controlled means for releasing the gages, and means for moving the gages and the work-support angularly to locate the sole with a median line thereof coinciding with the median line of the work-support.

In testimony whereof I have signed my name to this specification.
